United States Patent Office

Des. 195,942

Patented Aug. 13, 1963

195,942

PANELLING MATERIAL OR THE LIKE

Colman Zola, 58 Tamarack Way, Pleasantville, N.Y.

Filed May 7, 1962, Ser. No. 69,997

Term of patent 7 years

(Cl. D13—1)

FIG. 1

FIG. 2

FIG. 1 is a front view of a panelling material showing my new design; it is to be understood that the design is repeated both horizontally and vertically the length and width of the panelling material; and

FIG. 2 is a perspective view of the same.

The undisclosed side is substantially like the side shown.

I claim:

The ornamental design for a panelling material or the like, as shown and described.
